United States Patent Office.

LEONARD L. JACKSON, OF PATERSON, NEW JERSEY, ASSIGNOR TO HIMSELF AND JOHN FRAME, OF MIDDLETOWN, NEW YORK.

Letter's Patent No. 67,766, dated August 13. 1867.

IMPROVED BEDSTEAD FASTENING.

The Schedule referred to in these Letters Patent and making part of the same.

TO ALL WHOM IT MAY CONCERN:

Be it known that I, LEONARD L. JACKSON, of Paterson, in the county of Passaic, and State of New Jersey, have invented a new and useful improvement in Bedstead Fastening; and I do hereby declare that the following is a full, clear, and exact description thereof, which will enable others skilled in the art to make and use the same, reference being had to the accompanying drawings forming part of this specification.

Figure 1 is a top view of my improved bedstead.

Figures 2, 3, and 4, are detail views, partly in section, showing different ways in which the fastening may be secured.

Similar letters of reference indicate corresponding parts.

My invention has for its object to furnish an improved bedstead fastening, simple in construction, reliable in operation, and which will enable the bedstead to be easily and quickly set up and taken down. And it consists in slotting the ends of the side rails of the bedstead in such a way that one or both the arms or parts thus formed shall have sufficient elasticity to allow the dove-tailed tenon formed upon its end to be sprung into the dove-tailed mortise formed in the posts; and in the manner in which the slotted ends of the said side rails are secured in place.

A are the end rails, which are secured to the posts B in the ordinary manner. C are the side rails, upon the ends of which are formed dove-tailed tenons, fitting into dove-tailed mortises formed in the posts B, as shown in figs. 2, 3, and 4. The ends of the side rails C are slotted in such a way and for such a distance that one or both the arms or branches thus formed may have sufficient elasticity to enable the dove-tailed tenon to be readily sprung into and out of dove-tailed mortises formed in the posts. The slotted ends of the rails C may be secured in place in the posts in various ways; as by a swivelled thumb-screw, D, the forward end of which is swivelled to a plate attached to the lower edge of the upper arm of the slotted end of the rail, and which passes through a nut let into or secured to the lower arm of said rail, so that by turning the said screw in one direction the arms of the rail will be drawn towards each other so that the tenon may be readily passed into or taken out of the mortise, and by turning the screw in the other direction the arms of the rail will be spread apart so as to fit the mortise, securing the rail and post firmly together.

This construction I prefer; but if desired the arms of the rail may be spread apart by a set-screw, E, passing through a nut secured to the lower arm, and its forward end pressing against the lower edge of the upper arm, as shown in fig. 3. In this case the branched ends of the rail must be sprung into and out of the mortise by hand. Or the arms of the said rails may be spread apart to secure them to the posts by wedges F, driven between the said slotted arms, as shown in fig. 2. In this case also the slotted arms must be sprung into and out of the posts by hand.

I claim as new, and desire to secure by Letters Patent—

Fastening a bedstead-rail in place by placing its forked ends in slots, and forcing them apart by set-screws or wedges, as and for the purpose specified.
